SWEAT DRAIN ON WINDOWS

Filed Jan. 6, 1932

UNITED STATES PATENT OFFICE

KARL A. WEBER, OF LOS ANGELES, CALIFORNIA, ASSIGNOR TO WEBER SHOWCASE & FIXTURE COMPANY, OF LOS ANGELES, CALIFORNIA, A CORPORATION OF CALIFORNIA

SWEAT DRAIN ON WINDOWS

Application filed January 6, 1932. Serial No. 584,947.

This invention relates generally to window frame construction and particularly to the construction of window frames for refrigerator showcases. The glass in such showcases is commonly maintained at a temperature considerably lower than that of the air of the room in which the case is located so that if the air of the room is at all humid, the dew point is above the temperature of the glass, and more or less moisture condenses on the outer surface thereof and runs down onto the floor. Likewise, in cold weather water sometimes condenses on the inside surface of the exterior show windows of stores and accumulates in puddles on the floors of the display space.

An object of the present invention is to provide a simple yet effective window construction for draining condensation out below the glass to the inside of the showcase, or to the outside of the display window, as the case may be; thus preventing the accumulation of water on the floor of the building.

The invention will now be explained with reference to the drawing in which:

Figure 1 is a cross sectional view of a refrigerated showcase;

Figure 2 is a detail elevational view showing the construction of the sweat drain at the base of the display glass; and

Figure 3 is a view in the plane III-III of Figure 2.

Referring to Figure 1, a refrigerated showcase is depicted comprising a front wall 1, a floor 2, a rear wall 3, a top 4, and a display glass 5. Sliding doors 6 are provided in the wall 3, to permit the insertion or removal of articles to be displayed, and a rack 7 is provided for supporting the article to be displayed. Cooling pipes may be located in the upper part of the case as shown at 8, or they may be positioned elsewhere within the showcase as desired. A base designated 45 generally at 9, which may be of any desired construction, is provided to support the case at a desired elevation above the floor.

This invention relates only to the construction of the window frame for supporting and sealing the lower edge of the display glass 5,

and this frame will now be described with reference to Figures 2 and 3.

Referring to Figure 2, the wall 1 is preferably constructed with a wood framework which may be faced with tile 10 on the outside. It is the usual practice to line the lower part of the interior of a refrigerator showcase with metal to make it water-tight and prevent wetting of the wood walls and thus reducing their heat insulating value. Therefore, in accordance with the present invention, a sheet metal lining 11 is provided which extends along the floor 2, and up along the walls. On the front wall this metal lining is bent outwardly to form a shoulder 12 for supporting the rack 7 and is then molded along the top of the wall 1 to a point 13 from which it is bent upward parallel to the front face of the glass 5 and then outward to form a lip 14. The lower edge of the glass 5 is spaced from the upper surface of the sheet metal where it overlies the top of wall 1 by blocks 16. These blocks are spaced horizontally along the edge of the glass to provide a drainage space therebetween. Likewise, blocks 17 are positioned at intervals between the front face of glass 5 and the upturned portion 19' of the sheet metal, (for convenience in the description, the portion of the sheet metal 11 overlying the top of wall 1 will be called the sheet metal sill).

To secure and maintain the lower edge of glass 5 against blocks 17 a metal retaining strip 18 is provided. This strip extends longitudinally above the metal sill 19 and is secured in place by screws 22 screwed into the wall 1. Washers 20 are inserted between the metal sill 19 and the strip 18 to separate them and permit drainage of water therebetween. The forward edge of strip 18 is bent upward parallel to the rear surface of the glass 5 and the top edge is folded over as shown at 21 to contact with the glass.

It is sometimes desired to provide a tray immediately back of the lower edge of the glass in a refrigerator showcase, and in such cases the strip 18 may be extended upwardly and rearwardly from the inner corner of wall 1, as shown, to form a trough-shaped receptacle. The trough so formed is sometimes

termed a spinach rack. It may be provided with holes 23 to permit drainage of any water that may accumulate.

To give the showcase a finished appearance, a metal nosing strip 24 is provided on the front upper corner of the wall 1. This nosing strip may be extended down a short distance over the front wall and be secured thereto by screws 25 passing into the wall. 10 Above the corner of the wall, strip 24 is bent back and upwardly to a point adjacent the front surface of the glass 5 and above the lip 14 of the extended metal sill 19. To make the nosing 24 rigid and to space it from the 15 front face of the glass 5, the inner edge may be extended downwardly to form a lip 26, and the lower edge of this lip may be crimped inwardly to form projecting portions 27 adapted to contact with the front face of the 20 glass at intervals.

When a showcase of the type described is in operation, the temperature within the case is usually maintained very low. That is, it may be in the vicinity of the freezing point 25 of water, whereas, the air outside of the case will usually be from 20° to 60° warmer. The glass 5 is therefore maintained at a temperature considerably below that of the air in contact with the outer surface thereof, and 30 if this air contains any appreciable amount of moisture, as it usually does, the glass sweats. That is, moisture condenses from the air upon the surface of the glass as a fog which increases until the water accumulates in drops 35 and flows down to the lower edge of the glass.

With the structure provided, such water flowing downward over the outer surface of glass 5 passes down between the edge 26 of the nosing strip and the glass, thence down 40 between the glass and the upturned portion 19' of the metal sill, and then along the top of the metal sill below the edge of the glass 5, and under the securing strip 18 to the inner 45 edge of the metal strip from which point it drains to the floor of the showcase. A drain (not shown) may be provided in the floor of the showcase.

Although a particular construction has been described for use in connection with a 50 showcase having a sloping glass front, it is apparent that the invention is also applicable to frames for supporting glass vertically, and is thus adaptable to standard window construction. Of course, if the invention is applied to the outer windows of a building, the nosing strip 24 and the upstanding edge 18 of the metal sill will form the interior portion of the frame, since moisture condenses on the inside of such windows and this invention 60 will be utilized to drain such moisture to the exterior of the building.

I claim:

1. In window construction a pane of glass, means for supporting said pane, said supporting means comprising a sill member ex-

tending below the lower edge of said pane, means for spacing the lower edge of said pane from said sill, said sill member extending downwardly away from said pane on one side and extending upwardly in spaced relation from said pane on the other side, and a nosing extending upwardly over the said upwardly extending portion of said sill whereby said portion is concealed, the edge of said nosing being spaced from said pane to permit 70 drainage therebetween. 75

2. A window frame construction for joining the lower edge of a pane of glass to a wall supporting it comprising, in combination, a sheet metal sill member resting on top of said wall beneath the lower edge of said pane and extending outwardly and downwardly over the edge of said wall on one side and extending upwardly parallel to but spaced from the face of said pane on the other side, means for spacing the lower edge of the pane from the portion of said sill therebelow, and means secured to said sill on said one side for maintaining the pane in desired spaced relation to the upwardly extending portion of said sill 80 85 on the other side.

3. A window frame construction for joining the lower edge of a pane of glass to a wall supporting it comprising, in combination, a sheet metal sill member resting on top of said wall beneath the lower edge of said pane and extending outwardly and downwardly over the edge of said wall on one side and extending upwardly parallel to but spaced from the face of said pane on the other side, means for spacing the lower edge of the pane from the portion of said sill therebelow, means secured to said sill on said one side for maintaining the pane in desired spaced relation to the upwardly extending portion of said sill 90 95 on the other side, and a sheet metal nosing strip secured to the other side of said wall and extending upward over the edge thereof to a point adjacent but spaced from the face of said pane and above the upturned edge of 100 105 said sill member.

4. A window frame construction as described in claim 3, further characterized in that the edge of said nosing strip adjacent said pane is crimped toward said pane at intervals along its length to contact with the face of said pane and thereby uniformly space the major portion of said edge from said pane. 110

5. In refrigerator case construction, an enclosure, a portion of the wall of which comprises a pane of glass, a wall of greater thickness than said pane positioned therebelow, a sheet metal sill extended from the interior of said wall out over the top of said wall below the edge of said pane and upturned adjacent the outer surface of said pane but spaced therefrom, blocks between the lower edge of said pane and said metal sill, and other blocks 120 125 between the front edge of said pane and said 130

upturned edge for spacing said pane from said sill, a securing strip extending along the top of said metal sill inside of said pane and in contact therewith for holding it against
5 said last-named spacing blocks, means for securing said strip to said wall in spaced relation to said metal sill to permit drainage thereunder, and a metal nosing strip secured to the outer edge of said wall, and extending
10 upwardly and rearwardly to the front face of said pane at a point above the upturned edge of said metal sill.

Signed at Los Angeles, California this
22nd day of December, 1931.
